UNITED STATES PATENT OFFICE.

ROSANNA ROONEY, OF NEW YORK, N. Y.

DESIGN FOR A GARMENT-HANGER.

SPECIFICATION forming part of Design No. 32,778, dated June 5, 1900.

Application filed May 2, 1900. Serial No. 15,277. Term of patent 7 years.

To all whom it may concern:

Be it known that I, ROSANNA ROONEY, a citizen of the United States, and a resident of the city of New York, borough of Manhattan, 5 in the county and State of New York, have invented and produced a new and original Design for a Garment-Hanger, of which the following is a specification, reference being had to the accompanying drawings, forming a part thereof, in which—

Figure 1 is a perspective view of a garment-hanger viewed from the front and embodying the features of my design, and Fig. 2 is a rear elevation of the garment-hanger.

15 The leading features of the design consist in the oppositely-extending shoulder-supports A and A' and the curved section B between the shoulder-supports, which connects with and rises above the highest points at the upper surfaces of said supports.

The minor features of the design consist in

the continuous curved line forming the bottom contour of the holder, the semicircular formation of the section B and gradual taper of the upper edge of the section B in direction of the front of the hanger, the inclination of the back and outer side surfaces of the section B, and the merging of said surfaces into the upper and back surfaces of the shoulder-supports A and A'. 25 30

Having thus described my invention, I claim as new and desire to secure by Letters Patent—

The design for a garment-hanger herein shown and described. 35

In testimony whereof I have signed my name to this specification in the presence of two subscribing witnesses.

ROSANNA ROONEY.
